WILLIAM KAHN, OF NEW YORK, N. Y.

DEVICE FOR HANDLING LINOLEUM.

1,403,692.

Specification of Letters Patent. Patented Jan. 17, 1922.

Application filed March 11, 1919. Serial No. 281,980.

To all whom it may concern:

Be it known that I, WILLIAM KAHN, a citizen of the United States, and resident of the city of New York, in the county of New York and State of New York, have invented a certain new and useful Device for Handling Linoleum, of which the following is a specification.

This invention relates to a device for unrolling, measuring, cutting, and general handling of rolls of linoleum in stores, shops, or in similar situations. At the present time this work is performed by placing the roll horizontally upon the floor and unrolling it along the floor, with the result that as the roll is very heavy, usually between four and five hundred pounds, injury is frequently caused to the linoleum, for the reason that each part of its area (the long and very narrow strip at the point of tangency of the roll) is in turn subjected to the entire weight of the roll as it passes thereover in the unrolling. Such unrolling of the roll is particularly injurious to the linoleum during the winter months, due to the material composing the linoleum becoming hardened by the cold temperature and hence often cracking under the great weight of the roll during unrolling. For this reason much care has to be exercised in maintaining the room where the linoleum is stored particularly warm in wintertime, and when such goods are delivered to the merchant in cold weather the rolls have to be maintained in the warm room for over twenty-four hours before they may be unrolled without absolute danger of cracking, which requirement of course causes great inconvenience since such goods may have to be at once needed for demonstration and sale. Much inconvenience is also caused in moving the roll of linoleum about the floor, as it requires two or more persons to lift it, and very often such help may not be available. The principal object of my invention is to provide simple and inexpensive means for conveniently and efficiently unrolling, measuring, cutting off, and otherwise handling rolls of linoleum, and to avoid all of the aforesaid disadvantages.

Other objects and advantages will hereinafter appear.

In the accompanying drawings.—

Fig. 1 is an end elevation of the general carriage and of the linoleum roll mounted thereon in operative position.

Fig. 2 is a plan view of one of the end carriages.

Fig. 3 is a front elevation of the general carriage shown in Fig. 1.

A roll 1 of linoleum is provided with a bar 2 passing through the centre thereof, and the ends 3 of said bar are mounted upon independent carriages 4 which together with the bar 2 constitute one general carriage that sustains the roll in horizontal position and maintains it clear off the floor 5. Each bar-end 3 is mounted upon its carriage 4 by being seated within a yoke 6 thereof provided upon a supporting vertical post 7 which is secured to a base-frame 8 having wheels 9. The retaining yoke 6 is made of cast-metal and has a shank 10 fitting into the supporting post 7 which is of tubular metal, and a pin 11 driven through said shank and the post firmly secures the post and yoke together. Said post is fitted at its lower end into a hub 12 of the base-frame 8 which is made of suitable cast-metal, spider-arms 13 extend from the hub 12 and join it with the square sides 14 of frame 8; and a pin or pins 15 driven through said hub and the post renders these parts firmly secured. The wheels 9 are located at the corners of the frame 8 where the frame-sides 14 join, and the fork 16 of each wheel is pivoted about a stud 17 secured to the frame, whereby the axis of each of the wheels 9 is adaptable to revolve in a horizontal plane.

When it is desired to unroll and cut off a portion of the linoleum from the roll 1 in demonstrating and selling the goods the general carriage, comprising the independent carriages 4 and the sustaining-bar 2, is shifted to dispose the roll carried thereby in proper location upon the floor of the store. Due to the freedom of the axes of wheels 9 to revolve horizontally said general carriage may be ridden along the floor either in the direction of the axis of the roll, transversely to such direction, or diagonally. The bar-ends 3 may be held against longitudinal displacement in the yokes 6 either by the mere weight of the roll 1, or to insure further security against such displacement, pins 18 may be inserted through the bar 2 at each side of the yoke. The general carriage and the roll thereon having been thus disposed in proper location upon the floor of the store the leading edge of the roll may be drawn and a portion of the linoleum unwound from the roll in the man-

ner shown in Fig. 1. Said unwound portion is spread upon the floor and a desired length thereof may be measured and cut off from the roll of linoleum.

5 It will be evident that by means of the carriage the unrolling, measuring, cutting off, and general handling of the linoleum is greatly facilitated and the work may be performed in a convenient, rapid and efficient manner. And due to the roll of linoleum being constantly elevated above the floor so that its weight does not rest upon the unrolling portion all of the above mentioned injuries to the linoleum and losses 10 thereof heretofore experienced are fully avoided, and the goods may be handled in the store as conveniently in winter as in summer without requiring particular warming. By means of the carriage one person 15 may easily and conveniently move any heavy linoleum roll about the floor without requiring assistance. The rolls may consequently be made bigger in diameter than heretofore and thereby result in reducing 20 waste and remnants, such rolls having been limited in weight on account of the difficulty in handling, and cracking or injuring in the unrolling.

Variations may be resorted to within the 25 scope of the invention.

Having thus described my invention, I claim:—

1. A device for handling linoleum comprising the combination of a removable bar 30 adapted to pass through the centre of a linoleum roll, an independent self supporting carriage at each end of said linoleum carrying bar each including a self support-

ing wheeled base-frame, a support on each base frame, and an open yoke at the extremity of each of said supports for lowering and seating the ends of the linoleum carrying bar thereinto for placement of the linoleum in operative position for handling. 40

2. A device for handling linoleum to prevent cracking thereof in wintertime comprising the combination of a removable bar adapted to pass through the centre of a linoleum roll, an independent self supporting auxiliary carriage at each end of said linoleum carrying bar including a self-supporting wheeled base-frame, a support on each base-frame, and means at the extremity of each of said supports to receive and retain the ends of said linoleum carrying bar when lowered thereinto in a vertical direction for placement of the linoleum in operative position for handling. 45

3. A device for handling linoleum rolls comprising a general carriage having the 50 combination of a removable bar adaptable to pass through the centre of a linoleum roll, an independent self-supporting carriage for each end of the linoleum carrying bar including a self-supporting wheeled base-frame, a support on each frame, and means at the extremity of each of said supports adapted to receive and retain the ends of said linoleum carrying bar for placement of the linoleum in operative position for 55 handling. 65

Signed at the city of New York, in the county of New York, and State of New York, this 10th day of March, A. D. 1919.

WILLIAM KAHN.
